COMBINED CHAIR AND UTILITY CART

William A. Schnapp, Waterford, Mich.

Application March 4, 1959, Serial No. 54,842

Term of patent 14 years

(Cl. D14—3)

Fig. 1 is a side elevational view of a combined chair and utility cart, embodying my new design.

Fig. 2 is a view taken at right angles to the view shown in Figure 1.

Fig. 3 is a perspective view.

I claim:

The ornamental design for a combined chair and utility cart, as shown.
